UNITED STATES PATENT OFFICE.

JAC BRYNILDSEN, OF CANBY, MINNESOTA.

DISPENSING LABEL-HOLDER.

No. 836,086.

Specification of Letters Patent.

Patented Nov. 20, 1906.

Application filed February 21, 1906. Serial No. 302,210.

To all whom it may concern:

Be it known that I, JAC BRYNILDSEN, a citizen of the United States, residing at Canby, county of Yellow Medicine, and State of Minnesota, have invented certain new and useful Improvements in Dispensing Label-Holders, of which the following is a specification.

My invention relates to dispensing label-holders.

The object of the present invention is the provision of a label-holder adapted for holding labels, tickets, or other cards or sheets, especially adapted for holding druggists' labels, which will be adapted upon manipulation of keys by the operator to dispose the labels so that the operator can at once obtain the desired label.

The invention contemplates the provision of a label-holder and dispenser of the character set forth which may be rapidly and easily operated, will be adapted to accurately bring the desired label to the proper point to be taken by the operator, and which will be designed to sound an alarm when the operator operates any key which controls the delivery of a poison-label, thereby calling attention to this particular kind of label and guarding against dangerous mistakes.

The invention contemplates the provision of label-holding wheels or drums of novel construction, improved key-operated clutch mechanism for operating the drums, novel key-operated stop mechanism for arresting the turning of the drums in the necessary positions to deliver to the desired point the designated label, improved automatically-opening doors to display the label which has been positioned for delivery, and improved and novel alarm mechanism which will sound when a key controlling the delivery of a poison-label is actuated.

The invention is set forth hereinafter, and the novel features are recited in the appended claims.

In the accompanying drawings, Figure 1 is a front view of the complete machine; Fig. 2, a section on line *a b* of Fig. 1; Fig. 3, a section on line *c d* of Fig. 1; Fig. 4, a section on line *e f* of Fig. 1; Fig. 5, a detail illustrating the position and construction of the stop-pin guides and the arrangement of the stop-pin holes in the drum; Fig. 6, a view illustrating the door-operating mechanism, and Fig. 7 a detail of the alarm mechanism used in connection with the poison-label keys.

The operative parts are inclosed in a casing 1, in which is suitably journaled a shaft 2, having cones and ball-bearings 3 interposed between it and the label-holding drums or 60 wheels 4, which are loose on the shaft 2. As many of these label-holding drums may be employed as found convenient to accommodate the labels required in the particular business in connection with which the device is 65 used. The label-holding drums are divided into a plurality of compartments 5, in which are removable drawers 5', having springs 5" to hold packs of labels, all labels of the same kind being held in a given drawer. Springs 70 5"—one for each compartment—are secured to the drums and hold the drawers 5' therein.

Secured to the side of each label drum or wheel 4 is an annular ring 6, and secured to the shaft 2 is a clutch-wheel 7, having inclined pockets 8 and turning close within the ring 6. In the pockets 8 are loose balls 9. This construction provides a friction-clutch which permits free turning of the label-holding drums independently of each other and 80 independent stoppage thereof.

The side of each drum is provided with a series of stop-pin holes 10, arranged in spiral form, these holes corresponding in number to the compartments in the drum.

Secured to the casing 1, two being employed for each label-holding drum, are stop-pin-holding strips 11, having together a number of stop-pin-guide holes 12, corresponding to the number of stop-pin holes 10 and the 90 number of compartments in the drum. The holes 12 are arranged at an angle of substantially forty-five degrees to the horizontal.

Stop-pins 13, having bent ends 14, are slidably mounted in the stop-pin-guide holes 95 12, and the bent ends 14 are positioned to be received in the proper ones of the holes 10. The arrangement is such that on the actuation of a given stop-pin it selectively engages the proper stop-pin hole 10 and arrests the 100 turning of the drum 4, so that the proper compartment holding the desired label will be in the proper position for delivery to the operator.

Separate keys 15 independently control 105 the various stop-pins, there being as many keys for each drum as there are stop-pins and compartments for that drum, so that on operating the proper key the proper stop-pin will select the stop-pin hole which will bring 110 the desired label-compartment in proper position for delivery of the label the operator

may desire and which is indicated on the key in question. Each key 15 is rigidly connected to a bell-crank lever 16, which is pivotally mounted at 17, and is connected by a rod 18 to a spring-bar 19, which is pivoted at 20, the upper end of the spring-bar being connected to the key stop-pin at 21.

Positioned adjacent each poison-key is a spring-contact 25, projecting freely from an insulating-block 26 and having a binding-post 27, which is in circuit with an electric bell 28, via a wire 29, with included battery 30, while the bell is also in circuit with the metal frame of the machine by circuit-wire

15 31. When a poison-label key is operated, it touches the contact 25 and closes the electric-bell circuit, the bell continuing to ring as long as the bell is depressed, and thus indicating the dangerous character of the label sought.

20 Secured to the shaft 2 is an annular clutch member 40, and turning loosely on the shaft and located within this clutch member 40 is a clutch-wheel 41, having inclined pockets 42, in which balls 43 are loosely positioned. A key 44 is connected to the wheel 41 by the lever 45, pivoted at 46 to a rod 47, connected to lever 45.

In the frame 1 opposite the respective drums 4 are hinged doors 50 in front of openings 50' in the casing in front of each drum. The doors 50 are hinged at 51 and have angle-pieces 52, operable by levers 53, pivoted to casing 1 at 54 and connected to the spring-levers 19 by springs 55. Springs 54' hold the levers 53 in normal position. All the spring-levers 19 are connected by individual springs 55 to the lever 53, which controls the doors for the drum 4, operated by that set of keys.

35 The drums 4 are provided with holes 56—40 one for each compartment—into which a pin 57 may be pushed by the operator to lock the drum when it has been checked by the proper stop-pin 13.

In operating the machine, suppose it is desired to obtain a quinin-label, the operator first depresses the key 44, which causes the parts 40 and 41 to become clutched, thereby turning the shaft 2 and causing the various clutches which actuate the label-drums to all 45 clutch their drums and give them a turn on the ball-bearings 3. The operator then depresses the key bearing the word "Quinin" and in doing so causes the stop-pin 13 to be projected, and as soon as the hole 10 corresponding to the quinin-label compartment comes in line with the actuated stop-pin 13 the stop-pin snaps into said hole by the action of the spring-bar 19, thus immediately arresting the drum with the quinin-compartment 50 opposite one of the doors 50, which thereupon automatically opens, and the operator can obtain the label. Before releasing the quinin-key the operator pushes in the pin 57 to lock the drum where stopped. The pin

57 is pulled out after the label is obtained, so the drum may be subsequently operated.

Having thus described my invention, what I claim as new, and desire to secure by Letters Patent, is—

1. In a dispensing label-holder, the combination with a rotary label-holder, of actuating mechanism, an automatic clutch for causing turning of the label-holder by the actuating mechanism, and means for arresting the rotary label-holder at desired points, 75 said means being adapted to lock the label-holder against rotation when engaged therewith.

2. In a dispensing label-holder, the combination of a plurality of independently rotatable and arrestable label-holders, independent automatic clutches for the respective rotary label-holders, means for actuating said clutches to rotate the label-holders, and means for independently arresting the rotary 85 label-holders at desired points.

3. In a dispensing label-holder, the combination with a rotary shaft, of a rotary label-holder mounted to turn freely in respect of the shaft, an automatic clutch for clutching 90 the label-holder to the shaft but which permits arresting of the rotary label-holder without arresting the rotation of the shaft, means for arresting the rotation of the label-holder at desired points, actuating means, 95 and an automatic clutch for transmitting the motion of the actuating means to the rotary shaft.

4. In a dispensing label-holder, the combination with a plurality of independently-100 rotatable label-holders, of a rotary shaft, independent automatic clutches for automatically clutching the respective label-holders to the said shaft but which permit independent arrest of said label-holders without effecting the rotation of the shaft, means for independently arresting the rotation of the respective label-holders at various points, 105 actuating means, and an automatic clutch for transmitting the motion of the actuating means to said shaft.

5. In a dispensing label-holder, the combination with a rotary label-holding wheel or drum having a plurality of radial pockets, of 115 radially-slidable label-holders in the respective radial pockets, means for holding said label-holders releasably in said pockets, means for turning the drum, and means for arresting the drum at desired points.

6. In a dispensing label-holder, the combination with a casing having a door which closes a delivery-opening, of a rotary label-holder positioned so that the labels may be presented to the opening closed by said door, means for actuating the label-holder to thus 120 present the labels, and means for automatically opening the door when the desired label is presented thereto.

7. In a dispensing label-holder, the combination with a rotary label-holding drum having means for holding labels at different points thereof, and provided with a plurality of stop-pin openings arranged in the form of a spiral, a stop-pin guide, independent stop-pins guided by said guide adapted to selectively engage the stop-pin openings to arrest the drum, keys controlling the respective stop-pins, and yieldable connections between the keys and the stop-pins, whereby the selected stop-pin is made to snap into its opening when in register therewith.

5 In testimony whereof I hereunto affix my signature in presence of two witnesses.

JAC BRYNILDSEN.
